LOUIS STEINBERGER, OF BROOKLYN, NEW YORK.

BINDING-POST.

1,206,737.

specification of Letters Patent. Patented Nov. 28, 1916.

Application filed July 18, 1913, Serial No. 779,701. Renewed August 15, 1916. Serial No. 115,117.

To all whom it may concern:

Be it known that I, LOUIS STEINBERGER, residing at Brooklyn, in the county of Kings and State of New York, have invented certain new and useful Improvements in Binding-Posts, of which the following is a specification.

This invention relates to a novel construction of binding posts particularly adapted for effecting a quick and substantially perfect contact with a conductor terminal.

I seek among other things, to provide a binding post which is simple and compact in construction, which may be manufactured at low cost, and which is capable of withstanding a considerable degree of maltreatment, and to which the conductor terminal may be effectively and correctly connected by an extremely simple operation, and which will hold the conductor terminal against accidental displacement.

Among the particular objects to be accomplished by the aid of my invention, are the following:—I. To provide a binding post which may be embedded in a fistic material so as to have only a very small portion of itself projecting beyond the surface of the fistic material, this portion being thus protected against likelihood of injury. II. To provide a tubular member, and to provide within the tubular member a detachable mechanism comprising a clamp bodily detachable and adapted to serve as the immediate means for attaching a conductor terminal. III. To provide a detachable closure for the upper end of the tubular member referred to having a substantially central aperture extending longitudinally of the tubular member, to provide a stem having a head formed upon its outer end, the stem projecting through the aperture of the closure, and to provide means beneath the closure mounted upon the inner end of the stem for yieldingly maintaining the head in contact with the closure, whereby to form a bodily detachable spring clamp between the head and the closure, and to adapt the opposing faces of the spring clamp thus formed so as to facilitate the correct positioning of a conductor terminal between said opposing faces. IV. To form one of the opposing faces of the spring

clamp into a semi-spherically convexed surface, to form the other of the opposing faces of the spring clamp into a correspondingly semi-spherically concaved surface, to provide a conductor terminal with a semi-spherical depression adapted to be engaged by the semi-spherically convexed portion of the spring clamp, and to provide the conductor terminal with a semi-spherically convexed surface adapted to be received in the semi-spherically concaved portion of the clamp. V. To provide a binding post comprising a spring clamp, to provide a conductor terminal adapted to be clamped in such clamp, and to shape the clamping faces of the clamp and the faces of the conductor terminal in such manner as to coöperate to effect a substantially perfect setting of the conductor terminal between the clamping faces of the clamp without especial care on the part of the operator.

Other objects and aims of the invention, more or less specific than those referred to above, will be in part obvious and in part pointed out in the course of the following description of the elements, combinations, arrangements of parts and applications of principles, constituting the invention; and the scope of the protection contemplated will be indicated in the appended claim.

In the accompanying drawings which are to be taken as a part of this specification, and in which I have shown a merely preferred form of embodiment of the invention: Figure 1 is a side elevational view of an arbitrarily chosen structure, a portion thereof being illustrated in vertical section, and a binding post constructed in accordance with the provisions of this invention being illustrated in connection therewith; Fig. 2 is a view in perspective of the several elements entering into the construction of the binding post illustrated in Fig. 1, the elements being illustrated in disassembled relation; Figs. 3 and 4 illustrate respectively plan and side elevational views of a conductor terminal adapted for use in connection with the binding post illustrated; and Figs. 5 and 6 are diagrammatic views illustrating a feature of the operation of the structure disclosed in the other figures.

This invention is a divisional application

of my co-pending application, Serial No. 721,692, and the structure shown herein is incidental, in a way, an improvement over a binding post structure illustrated in connection with my co-pending application Serial No. 698,008.

In my co-pending application, Serial No. 698,008, I have illustrated the same construction as that shown herein, except in so far as the formation of the opposing faces of the clamp and immediately associated parts is concerned.

In the co-pending application, No. 698,008, the opposing faces of the clamp are shown both to be convexed. This has been found to be a decided advantage over any structure of which I am aware, but I have ascertained that by making the opposing faces of the clamp one convex and the other concave, the advantages sought to be gained in the structure of the pending application are more pronounced. A single convex surface working in conjunction with the concave surface of the conductor terminal effects a desirably perfect setting of the conductor terminal irrespective of the form of the other face of the clamp. With both faces of the clamp convex, the conductor terminal is reversible, but to form the second face of the clamp with a concavity to correspond with the convexity of the first face, while it destroys the reversibility of the conductor terminal, it more easily and accurately effects the movement of the conductor terminal into a final and correct set.

I have also found it desirable to provide a surface portion surrounding the immediate clamping faces of the binding post, inclined relatively to said clamping faces, operating with a relatively similarly inclined portion of one of the clamping members, so as to form a sort of open mouth at all circumferential points into which the conductor terminal may be readily and conveniently thrust.

The structure illustrated in the drawings may be described in detail for a better understanding of the features of this invention, as follows:—

The reference 1 represents the base member of a spark plug having a threaded portion 2 for facilitating attachment of an engine or the like. An insulator portion 3 attached thereto is formed with a concavity 4 in its upper end and a casing 5 is fitted into said concavity and held by suitable means, such as a bolt 6. The upper end of the casing 5 is preferably internally threaded and fitted with a closure 7 having a head portion 8 extending radially beyond the casing, across the upper surface of the member 3, and having a down turned portion 9 engaging the outer annular edge of the member 3. The central portion of the upper surface of the head 7 is dished out

into a semi-spherically shaped concavity 10, the remaining portion of the upper surface of the head 7 being inclined outwardly and downwardly from the portion 10, as at 11, concentrically with the portion 10. An aperture 12 extends axially through the closure 7, opening centrally of the dish shaped portion 10, and a rod or stem 13 extends through the aperture having a head 14 at its upper end. The under surface of the head 14 is semi-spherically convexed, as at 15, with a convexity corresponding substantially to the concavity of the dish shaped portion 10. The lower portion of the rod 13 is fitted with a detachable head 16 for retaining a coil spring 17 interposed therebetween and the under surface of the closure 7, adapted for drawing the head 14 toward the dished surface 10.

The tension of the spring 17 may be readily adjusted by movement of the head 16 along the rod 13, as will be understood, and the clamp formed by the relation between the upper surface of the closure 7 and the under surface of the head 14 is adapted to effectually retain the conductor terminal when said terminal is introduced into said clamp.

The conductor terminal employed in connection with this device is substantially the same as to shape as that disclosed in connection with my co-pending applications above referred to, and comprises a portion 18 electrically connected to the conductor 19, and a relatively thin flat plate 20 extending therefrom, and having a slot 21 formed therein. Adjacent the inner end of the slot 21, the material of the plate 20 is dish-shaped, as at 22. Said dished portion 22 being substantially concentric with the inner end portion of the slot 21.

The material of which the conductor terminal is formed is preferably relatively thin and the dished portion 22 is formed therein by pressing the material in a die, so that the surface of the plate 20, opposite the dished surface 22, will be pressed outwardly, as at 23.

The portions 22—23 of the terminal are formed so as to provide a concavo-convex portion upon the plate 20, the concaved surface being shaped to correspond with the spherically convexed under surface of the head 14 of the binding post, and the convexed surface of the terminal being substantially parallel with the concaved surface thereof.

It is thus apparent that upon introducing the conductor terminal between the opposing faces of the clamp illustrated, it will not be necessary for the operator to exercise especially care in forcing the terminal to a positively defined final position. All that is required, is for the terminal to be introduced just sufficiently far for the semi-spherically

convexed surface of the head 14 to engage a portion of the semi-spherically dished portion of the terminal, whereupon the yielding pressure of the clamp, assisted by the co-operative effect of the dished portion 10 of the other clamp surface, will naturally induce the terminal to move, with a cam, or wedge-like action, into a substantially perfect set between the jaws of the clamp.

10 In introducing the terminal, the terminal should preferably be held in the position substantially as indicated by dotted lines in Fig. 1, the nose 23^a thereof being thrust along the surface 11 of the closure 7 and 15 against the under surface of the head 14. The nose 23^a is preferably tapered, as shown, to facilitate this action. With the terminal in the position indicated by dotted lines, in 20 Fig. 1, it is obvious that the normal weight of the terminal, and especially of the conductor 19, to which it is attached, will tend to press the terminal downwardly into the position shown in full lines. This movement of the terminal will take place almost 25 without any care on the part of an operator. It should be also noted that if an operator should force the terminal under the head 14, while the terminal is in a substantially horizontal position, the head would rise against 30 the tension of the spring 17 and immediately the operator removed his hand from the terminal, the spring action, supposing the terminal not to have been pushed home, will cause the terminal to bound upwardly 35 toward the position shown in dotted lines, whereupon the action heretofore described will immediately ensue. In case the weight of the terminal and the conductor 19 is so great as to prevent movement to the position 40 shown in dotted lines, then the parts will stand in the position shown in Fig. 5, wherein it is apparent that the engagement of the portion 24 of the terminal with a relatively inclined portion of the surface 15, 45 and the engagement of a portion, as 25, of the other clamp face with a relatively inclined portion of the surface 23 of the conductor terminal, will positively force the conductor terminal to its seat without any 50 further care on the part of the operator. Here it may be noted, that the action between the surface 15 and the part 24 is sufficient of itself to move the terminal to final position, even without the co-operation 55 between the parts 23 and 25. Likewise it is apparent that the action between the parts 23 and 25 is sufficient of itself to move the conductor terminal to final position without co-operative wedge action between the parts 60 15 and 24. One member of the clamp might therefore be substantially flat or even concaved, as shown in my co-pending application No. 698,008, so long as wedge action is provided between the terminal and the other 65 clamp member. To provide a wedge action

between both of the clamp members obviates the friction present in my former application and more than doubles the effectiveness of the wedge action tending to move the terminal to its seat.

In Fig. 6 I have illustrated diagrammatically a structure wherein the co-operating surfaces of the clamp and conductor terminal are frusto-conical, as distinguished from the semi-spherically curved surfaces 70 shown in the other figures. In this structure the cam action, though of substantially the same character as in the semi-spherical structure, is of maximum efficiency from the beginning. In the semi-spherical structure 75 the cam action begins gradually and increases as the terminal moves inwardly.

I am aware that it has been heretofore suggested in the art to provide clamping members between which a conductor terminal may be engaged in somewhat the same general manner as I have disclosed in my present, and in my pending applications, but within my knowledge such constructions have necessarily required the manual movement of the terminal into a substantially single position relatively to the clamping members ere the connection between the clamp has been of its maximum efficiency, either electrically or mechanically. By arranging the clamping surfaces of my binding post in the manner illustrated, and providing co-operatively formed surfaces upon the conductor terminal, as illustrated, 85 I have materially simplified the construction 90 and have entirely avoided the necessity for careful adjustment on the part of an operator. The parts co-operate in such manner as to effect a substantially perfect setting of the conductor terminal between the 95 clamp faces. The element of human carelessness may be disregarded.

While I have illustrated my binding post in connection with a spark plug, it is, however, obvious that the same is adaptable for 100 use in any other desired connection. The portion 7 of my structure may be regarded as a fixed element, and the portion 14 as a movable element or vice versa, and likewise the position of the concaved and convexed 105 surfaces of the clamp may be reversed so that the concaved surface would appear on the portion 14, and a convexed surface on the portion 7.

The manner of connecting my binding post to a support may likewise be altered within the scope of this invention, and does not depend upon the presence of the casing 110 5 for this purpose. The fixed member of the clamp may be supported in any manner desired.

As many changes could be made in this construction without departing from the scope of the following claim, it is intended that all matter contained in the above de- 115 120 125 130

scription or shown in the accompanying drawing shall be interpreted as illustrative only and not in a limiting sense.

Having thus described my invention, 5 what I claim as new and desire to secure by Letters Patent, is:—

The combination with a conductor terminal formed of a sheet of material having a part thereof pressed to form a convexed 10 surface portion at one side of the conductor terminal and a concaved surface portion at the other side thereof, of a binding post having a concavity therein to receive the convexed portion of the conductor terminal, 15 said binding post having a clamping member adjacent the concavity thereof con-

vexed to be received within said concavity, and means for yieldingly pressing said clamping member into said concavity comprising a rod extending from the center of 20 the concaved portion of the binding post into engagement with said clamping member, and a spring engaging said rod to urge said rod in a direction to move the clamping member toward said concaved portion. 25

In testimony whereof I affix my signature in the presence of two witnesses.

LOUIS STEINBERGER.
